United States Patent Office

Des. 206,253

Patented Nov. 15, 1966

206,253

COMBINED CABANA AND SOLARIUM THEREFOR

Mike Tecton, 5101 45th St. NW.,
Washington, D.C. 20016

Filed Sept. 16, 1965, Ser. No. 87,025

Term of patent 14 years

(Cl. D83—1)

FIG. 1 is a perspective view of a combined cabana and solarium therefor, embodying my new design;

FIG. 2 is a side elevational view thereof;

FIG. 3 is a top plan view thereof;

FIG. 4 is an end elevational view thereof;

FIG. 5 is a cross sectional view taken along line 5—5 of FIG. 2 showing a general cross sectional configuration.

I claim:

The ornamental design for a combined cabana and solarium therefor, substantially as shown.
